QUIVER FOR AUTOMATIC ARCHERY RANGE

Charles P. Sanzare, Philadelphia, Pa., assignor to Archery Lanes, Inc., Conshohocken, Pa., a corporation of Pennsylvania

Filed Dec. 15, 1964, Ser. No. 83,044

Term of patent 14 years

(Cl. D30—1)

FIGURE 1 is a right front perspective view of a quiver for automatic archery range showing my new design;

FIGURE 2 is a left front perspective view thereof;

FIGURE 3 is a top plan view thereof.

The bottom of the quiver is plain in appearance.

The dominant features of my design reside in the portions shown in full lines.

The broken line portion represents a conveyor for returning the arrows to the quiver and is shown fragmentarily for convenience of illustration. The arrow shown in the window is depicted for illustrative purposes only.

I claim:

The ornamental design for a quiver for automatic archery range, as shown and described.
